UNITED STATES PATENT OFFICE.

GEORGE H. BAUGHMAN, OF CHICAGO, ILLINOIS.

MANIFOLDING SALES-BOOK.

1,284,561.

Specification of Letters Patent. Patented Nov. 12, 1918.

Application filed June 25, 1917. Serial No. 176,783.

To all whom it may concern:

Be it known that I, GEORGE H. BAUGHMAN, a citizen of the United States, and a resident of Chicago, in the county of Cook 5 and the State of Illinois, have invented certain new and useful Improvements in Manifolding Sales-Books, of which the following is a specification.

My present invention relates to manifolding sales-books and more particularly to 10 that type known commercially as duplication sales-books wherein an original and a duplicate ticket is made and the sale tabulated upon a record card that forms a part 15 of the pad of tickets.

The object of my invention is the provision 20 of suitable means for securing a sales-pad to the covers of the book consisting of a clamp of novel construction that is adapted to firmly grasp and hold the pad engaged 25 thereby and at the same time permit its ready removal from the clamp. It has been found that the clamps and other devices employed for removably securing the pads 30 within the book covers will, owing to frequent use of the book, wear away and damage the cover members and it is therefore a further object of my invention to construct a book of this type that will overcome this inherent objection.

Other objects comprise the provision of a sales book that is neat in appearance, effective and dependable in its operation, strong and durable in construction and economical 35 to manufacture and I prefer to accomplish the divers objects of my invention by substantially the means hereinafter fully described. Reference will now be made to the accompanying drawings that form a part of 40 this specification, wherein,—

Figure 1 is a fragmentary perspective view of a duplicating sales book made in accordance with my invention, the same being shown in opened position to illustrate the 45 construction and arrangement of the parts thereof.

Fig. 2 is a fragmental top plan of the clamp and adjacent end of the sales book.

Fig. 3 is a transverse section thereof taken 50 on line 3—3, Fig. 2, looking with the arrows.

In the drawings I have employed similar characters to designate the same parts throughout the several views, and by reference to Fig. 1 it will be observed the binder 55 for the manifolding pad and record card

preferably comprises a front cover 5 and a back cover 6, that are made of rectangular shaped pieces of relatively stiff material, such as binder board, and are flexibly connected along adjacent end edges by a web 7 60 in order to readily permit the same to hinge whenever the book is opened or closed in the usual manner.

A duplicating pad is removably secured upon the back cover by a suitable clamp to 65 be hereinafter described, said pad consisting of a plurality of superimposed leaves 8, each folded upon itself so that the under portion of each leaf extends beyond the adjacent edge of the upper portion of said leaf whereby 70 a binding strip is provided through which staples 9, stitching, or other means are passed for the purpose of securing the leaves together in the form of a pad. Commercially this top member of each leaf is 75 designated as the "original" sales ticket while the other member provides a "duplicate" sales ticket and in order to transfer the entry from the original to the duplicate ticket a sheet of manifolding or carbonized 80 paper 10 is bound upon the top of the pad so that it may be readily inserted between the two members of each leaf prior to the entry of a sales record thereon.

Bound into this pad preferably upon the 85 bottom thereof is a sheet of tag-board or other substantial paper that is longer than twice the length of the pad. This record strip is folded upon itself intermediate its 90 ends so that the upper portion thereof forms a back 11, for the pad of tickets, while the lower portion is printed or ruled to provide a record card 12 whereon condensed entries 95 may be made of the amount of the individual sales recorded upon the corresponding tickets that have been removed from the pad. The edge of the back 11 opposite the fold is secured to the bottom of the pad by the same means that bind the leaves together and the folded edge of the back and record 100 card extends beyond the folded lower edges of the leaves of the pad in order that the same may be removably held by a suitable clamp. It will be seen the record card 12 is hidden from view below the pad but is readily accessible by simply lifting the bound edge of the pad and laying it flat upon the counter or table when the entry is made thereon.

This clamp above alluded to consists of 110

a piece of metal 13 bent longitudinally, U-shaped in cross-section and has one of its parallel members riveted or otherwise rigidly secured to the lower edge portion of 5 the back cover 6 of the binder. Suitable projections such as impaling pins 14, 14 project upward from the lower member of this metal strip so that they may be inserted through the folded extended portion of the 10 back of the pad. The upper member of this plate has its end portions provided with knuckles 15, 15, into which the ends of a suitable swinging clamping member, such as a bail, 16 are inserted. I prefer to construct 15 the bail shown of a piece of wire or the like having its ends bent backwardly as shown so that said ends may be inserted into the outer ends of the knuckles 15 but this however is not essential and the clamping member 20 may comprise other equivalent structures without departing from the principle involved. After the back of the pad has been engaged or impaled upon the pins 14 the bail, which has been previously raised to 25 permit the insertion of the pad back, is lowered upon the latter immediately back of the pins and further pressure upon the bail will force the same securely down upon the pad back and prevent its accidental removal 30 from the clamp. A suitable concave recess 17 is made in the upper member of the metal strip to facilitate the releasing or raising of the bail 16 whenever it is desired to remove or insert a pad, and I also prefer to extend 35 the metal of the strip forwardly upon each side thereof as shown at 18 in the drawings, in order to permit the central portion of the bail to be snapped or sprung over the same when being moved to a lowered or clamping 40 position.

I have illustrated and described herein a single form of my invention which it will be obvious may be modified without materially departing from the principles involved, the drawings being in a sense merely diagrammatic. For example in lieu of impaling pins 14 small teats or embossments 45 may be made in the metal strip of the clamp so that the bail will press the pad back down 50 at the rear of said embossments. All such changes are understood as contemplated within the scope of the appended claims.

What I claim as new is:—

1. A clamp for sales-book pads consisting of a metal plate of substantially U-section, 55 an upstanding element formed upon the lower member of said plate upon which a portion of a pad is disposed, and a bail carried by the upper member of said plate and adapted to be moved past said upstanding element to coöperate with said pad portion. 60

2. A sales book comprising flexibly connected covers, a pad of leaves, and a clamp for removably securing said pad to one of said covers consisting of a plate of U-shaped cross section secured adjacent one edge of one of said covers, and provided with knuckles, impaling pins projecting upwardly from the lower member of said plate, a bail carried by said knuckles and adapted to co- 65 operate with said pins, and an extension on the upper member of said plate projecting into the path of movement of said bail and past which said bail is adapted to be moved whereby the bail is adapted to coöperate 70 with said pins. 75

3. A clamp for sales-book pads comprising a suitable plate provided with a plurality of pins adapted to receive a portion of the pad, a bail pivotally mounted on said 80 plate and movable to coöperate with said pins, and an extension projecting from said plate into the path of said bail past which said bail is adapted to be moved whereby the latter is adapted to coöperate with said 85 pins. 90

4. A clamp for sales-book pads and the like comprising a suitable plate having a portion extended above the same and provided with knuckles, upstanding members 95 on the lower portion of said plate, and a bail carried by said knuckles a portion whereof is adapted to be moved below and into substantially vertical alinement with said knuckles whereby leaves are adapted to be clamped between said bail and plate and impaled upon said upstanding members. 95

Signed at Chicago, county of Cook, and State of Illinois, this 22d day of June, 1917.

GEORGE H. BAUGHMAN.
